UNITED STATES PATENT OFFICE.

MATHIAS WAGNER, OF ATLANTA, GEORGIA.

SAW-SHARPENING MACHINE.

1,153,982.

Specification of Letters Patent. Patented Sept. 21, 1915.

Application filed January 13, 1915. Serial No. 2,054.

To all whom it may concern:

Be it known that I, MATHIAS WAGNER, citizen of the United States, residing at Atlanta, in the county of Fulton and State 5 of Georgia, have invented certain new and useful Improvements in Saw-Sharpener Machines; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

This invention relates to improvements in saw-sharpening machines.

The object of the invention is to provide means for reciprocating a file over the saw 20 teeth, and in one of the reciprocating movements, the file is elevated to adjust the saw for the next succeeding tooth, the file in the succeeding movement of its reciprocation being automatically lowered to file the tooth.

25 The invention also aims to provide new and improved means for angularly disposing the saw with reference to the file, to sharpen a tooth at any desired angle within a given range.

30 The invention also relates to improvements in the means employed for reciprocating the file, and the means employed for raising and lowering the file in its reciprocation.

35 The invention also comprehends improvements in the specific details of construction and arrangement of parts which will be hereinafter described and particularly pointed out in the claims.

40 In the accompanying drawings:—Figure 1 is a plan view. Fig. 2 is a side elevation. Fig. 3 is an enlarged detail perspective view of the front end of the machine. Fig. 4 is a detail perspective view of the end of the 45 base and the saw support. Fig. 5 is a detail perspective view of the pawl and its support, for rotating the saw. Fig. 6 is a detail section of the file holder. Fig. 7 is a detail view of the end of one of the cam levers and its cushion. Fig. 8 is a detail view of the pawl for rotating the saw. Fig. 9 is a detail view of the saw support.

1, indicates a base, provided with standards 2, forming bearings for a shaft 3, on 55 which is mounted a wheel 4. On the shaft

3, are two cams 5 and 6, the operative faces of each being substantially diametrically disposed; and on the side of the wheel 4, is a cam 7. Also mounted on the frame 1, is a support 8, including a guide rod 9. Reciprocating, and tiltably mounted on the guide rod 9, is a slide plate 10, provided with depending arms 11 and 12. In the arm 12 is formed a socket 13, to receive one end of a file 14, and in the opposite arm 11, is a slot 15, which receives a bolt 16, provided on its inner end with a socket member 17, which is held in adjusted position by the head of the bolt 16.

The lower end of the arm 11, is formed with a flange 19, through which extends a screw 20, which engages in a depression 21, in the under side of the socket 17, and extending through the arm 11, above the socket, is a lug 22, formed with a threaded 70 opening 23, which receives a screw 24, which extends above the slide; to be in convenient reach of the operator.

Obviously by adjusting the screws 20 and 24, the socket 17, and the file 14, may be regulated so as to properly engage the respective teeth of the saw.

Pivoted to the arm 12, is a connecting rod 25, the opposite end of said connecting arm being pivoted to a pin projecting from the 85 wheel 4. As the wheel 4, rotates, it reciprocates the slide on the guide bar 9, which in turn reciprocates the file across the teeth of the saw, as will be readily understood.

In one movement of the reciprocation of the file, the cam 5, engages a cam lever 26, pivoted at 27, to the base 1, its forward end engaging an opening 27^a, formed in a transverse lever 28, pivoted at 29, in a standard 30, adjustably mounted as at 31, on the base 90 1. The inner end of the arm 28, is provided with a flange 32, which engages the under side of the slide plate 10, and elevates the file from the saw teeth, to permit the saw to 95 freely rotate one tooth, as will be presently described. The outer end of the arm 28, operates in a guide 33, mounted on the frame 1, the movement being limited by a set screw 34. The cam 6, operates on a cam lever 35, pivoted at 36, to the base plate 1, its forward end being pivoted to a slidable post 37, the arm 28 passing through the slot in said post. The lever 35, is extended at its forward end, and engages the end of a goose-neck lever 39, pivoted at 40, and its lowered 105 110

end being in engagement with a spring 41, mounted between said lever and the frame, the tension of the spring being adjustable by regulating a screw 41^x. The upper end of the post 37, is reduced to form a stem, which extends through a slot 45, in a lever 46, pivoted to standard 30, extending from the frame, and on the inner end of said lever, is a roller 48, which engages the upper surface 10 of the slide 10, a spring 48^a, being interposed between the lever 46, and a shoulder on the post 37. The object of this construction is to tilt the slide downwardly to cause the file to engage with the tooth in the sharpening operation, it being evident that upon operation of the cam 6, the lever 46 will be so tilted as to engage the slide 10, and hold the file in position in the saw teeth.

The base 1, is formed with an arcuate slot 50, and pivoted to said base, adjacent the slot, at 51, is a swinging saw carrying frame 52, same comprising upper and lower plates 53, which engage the upper and lower surfaces of the base 1, and extending through the slot 50, and connecting the upper and lower plates, is a bolt 54, to clamp the frame in adjusted position. Depending from the lower plate 53, is a bar 55, slotted at 56, and provided at its lower end with a cross bar 57. Operating in the slot 56, is a slide block 58, formed with side grooves 59, in which fit the walls of the slot 56. The block 58, is formed with a slot in which is a collar 60, secured to a screw 61, the latter engaging a threaded opening 62, formed in the cross bar 57, so that by turning the screw, the block 58, may be adjusted vertically, in either direction. Extending from the block 58, is a screw 63, having a thumb nut 64, and a bushing 65, which engages an opening formed in a circular saw 66.

By adjusting the bolt 54, the frame can be turned at an angle to the longitudinal axis of the file, and by adjusting the screw 61, the saw can be raised or lowered, whereby the proper angle may be obtained to file the teeth of the saw, as may be desired.

Pivottally mounted on the frame 1, at 70, is a lever 71, provided at one end with a set screw 72, which engages a stud 73, projecting from the slide 74, suitably mounted on the base 1. The inner end of the slide is positioned to be engaged by the cam 7, when the wheel 4, rotates, consequently the lever 71, is rocked laterally with reference to the longitudinal axis of the file. On the outer end of the lever 71, is a pawl 76, which engages the teeth of the saw, to rotate the latter to present the succeeding teeth to the file in the operation of the machine. The pawl 76, is formed with an elongated opening 77, a screw 78^x, extending through said opening to fasten the pawl to the lever 71, the elongated slot permitting of the pawl being tilted that it may be properly positioned

with reference to the angular disposition of the saw. The pawl is moved in one direction by the cam 7, while a spring 71^a, moves it in the opposite direction. In order to brace the pawl 76, when it is angularly disposed, adjustable slides 78^a, formed with slots 79, and held by set screws 80, are provided on the lever 71. Extending from the pawl 76, and to one of the slides, is a spring 82, to draw the pawl against a flange 78 75 formed on each slide 78^a, as clearly shown in the drawings. Two of these slides are provided so as to brace the pawl when it is turned to the right or left of its pivot, and the lever 71 is formed with several openings 80 83, to receive the screws of the slide, so as to adjust the position of the pawl with reference to the saw.

In operation, a circular saw is mounted on the bushing 65, and is clamped against the block by the wing nut 64, the angular position of the saw being determined by the adjustment of the standard through the medium of the bolt 54, as previously explained, the angle of the saw being set, according to 90 the desired angle of the cut of the teeth. The saw having been set, the file is adjusted in the slide, and upon rotation of the shaft, and when the various cams engage the respective levers, the file is moved in one direction of its reciprocation in engagement with the saw, and in its other movement, said file is elevated, and the pawl rotates the saw one tooth.

Assume the cam 5, is in engagement with 100 the lever 26, the slide carrying the file is elevated above the saw, and the wheel 4, is carrying the file back preparatory to making the next or filing stroke on the tooth. At this time, the cam 7, engages the end of the slide 73, and rocks the lever 71, on its pivot 70, and thereby pawl 76 is caused to engage 105 one of the teeth of the saw, and the latter is rotated to remove the previously sharpened tooth from under the file, and to present 110 another tooth to said file to be sharpened.

About at the time of completion of the idle stroke of the file caused by the action of cam 5, cam 6 engages its coöperating cam lever and elevates the end of rod 46, and causes the roller at the free end of the latter to force the slide, consequently the file, down into engagement with the saw for the sharpening operation, excess movement or pressure on said arm 46 being relieved by means of the spring 48^a. Of course, the cam 7 has passed the end of the slide 73, and the spring 71^a, has returned pawl 76, to its normal position.

Upon continued rotation of the shaft 3, the operation of the parts described continues, and the file is reciprocated and a new tooth is presented.

If it be desired to file the teeth at an angle, 136 the standard 55, is adjusted, and also the

pawl 76, is likewise adjusted, so that in the movement of the file, an angular cut is made on the tooth.

What I claim is:—

- 5 1. In a saw sharpening machine, the combination of a frame, a shaft mounted on the frame, a wheel on the shaft, cams rotatable with said shaft, a saw support, a rod on the frame, a sliding frame mounted on the rod 70
 10 and carrying a file to engage the teeth of a saw on the saw support, a connecting arm between the wheel and the slide to reciprocate said slide, a series of levers between one of the cams and the slide to rock said slide 75
 15 on the rod and the file carried thereby in direction of the saw tooth being sharpened, and a system of levers, one of which engages the under side of the slide to rock the latter on the rod and the file upwardly and away 80
 20 from the saw tooth, one of the latter on the rod system of levers being operated upon by one of the cams.

2. In a saw sharpening machine, the combination of a frame, a shaft mounted in the frame, a wheel on said shaft, cams rotated when said shaft is rotated, a guide bar, a slide slidably mounted on the guide bar, standards extending from the slide, one of said standards having a socket, the other 90
 30 said standard having oppositely disposed lugs formed with threaded openings, screws fastened through said openings, an adjustable socket member mounted in the standard and with which the screws engage to hold 95
 35 the end of the file and adjust the latter toward and from the slide, a connection between said slide and the wheel, a support to receive a saw being operated on by the file, means for rotatably adjusting the said support, means in the support for vertically adjusting a saw, means including a system 100
 40 of levers, one of which bears on the slide to force the file in contact with the tooth being sharpened, said levers being operated by one of the cams, a second system of levers, one of which engages under the slide to elevate the latter and operable by one of the 105
 45 cams, a pawl for rotating the saw, and means between one of the cams and the pawl 110
 50 for operating the latter.

3. In a saw sharpening machine, the combination of a frame, a saw support mounted on the frame, means for adjusting the saw vertically, means for angularly adjusting the saw on the support, a slide for carrying a file, means for reciprocating the slide, a pivoted lever engaging the side of the slide to elevate the file from a saw tooth, means for operating said pivoted lever, a second pivoted lever for lowering the slide to bring the file into contact with the saw tooth, a lever and post to operate said second mentioned lever, and a spring to relieve the strain on the slide when same is lowered.

4. In a saw sharpening machine, the com-

bination of a frame, a shaft mounted on the frame, a wheel carried by the shaft, a saw support on the frame, a slide carrying a file, a connection between the slide and the wheel to reciprocate said slide, an arm to elevate the slide, a lever connected to the arm, a cam on the shaft to operate the lever, a second arm engaging the upper surface of the slide to lower the latter, a second lever for operating the second mentioned arm, a cam 75 on the shaft for operating the second mentioned lever, a lever mounted on the frame to move at right angle to the movement of the aforesaid levers, a horizontal slide between said horizontal lever and the cam on 80 the wheel to oscillate said horizontal lever, a pawl on the opposite end of said horizontal lever, means for mounting said pawl to move horizontally and laterally, gages on the horizontal lever against which the pawl 85 engages, a spring between one of said gages and the pawl to hold the latter in angular position, and a spring for operating said horizontal lever to return it to normal position after the saw has been moved.

5. In a saw sharpening machine, the combination of a frame, a saw support mounted on the frame, means for adjusting the saw vertically, means for angularly adjusting the saw on the support, a tiltable file carrying 95 slide, means for reciprocating the slide, means for tilting the slide to elevate the file from the saw tooth, means for tilting the slide in the reverse direction to bring the file into contact with the saw tooth, and means 100 to relieve the strain on the slide when same is brought into contact with the saw tooth.

6. In a saw sharpening machine, the combination of a frame, a saw support having vertical guides and mounted on the frame, a 105
 110 slide block mounted in the vertical guides, means for mounting a saw on the block, a screw for vertically adjusting the block in the guides, means including a slot and bolt between the support and frame to angularly adjust the saw support, a tiltable file carrying slide, means for reciprocating the slide, means for tilting the slide to elevate the file from the saw tooth, means for tilting the slide in the reverse direction to 115 bring the file into contact with the saw tooth, and means to relieve the strain on the slide when the same is brought into contact with the saw tooth.

7. In a saw sharpening machine, the combination of a frame, means for adjustably mounting a saw on the frame, a tiltable file carrying slide, means for reciprocating the slide, means for tilting the slide to elevate same away from a saw being operated upon, means including a pivoted lever for tilting the slide in the reverse direction to lower the slide to the saw, a spring engaging the pivoted lever to remove the shock from the saw 125 when the file engages a tooth, and means for 130

rotating the saw intermittently to present the teeth to the file to be sharpened.

8. In a saw sharpening machine, the combination of a frame, means for adjustably mounting a saw on the frame, a rotating cam, a pivoted pawl carrying lever, an adjustable abutment on the lever, a pawl loosely mounted on said lever and seated against the abutment, a spring for holding the pawl against the abutment, means for adjusting the position of the pawl, means between the lever and the cam to adjust the position of the pawl with reference to the saw tooth, a tilttable file carrying slide, means for reciprocating the slide, means for tilting the slide to operate upon a saw tooth, means for reversely tilting the slide to elevate the file from the saw tooth, and an adjustable file holder carried by the slide.
- 10 15 20 9. In a saw sharpening machine, the com-

bination of a support for a saw, means for intermittently rotating a saw, a file carrying slide, means for reciprocating the slide, an adjustable file holder carried by the slide, a pivoted horizontally disposed lever engaging the top of the slide, a pivoted horizontally disposed lever engaging the bottom of the slide, a spring acting to absorb the shock and strain of said two levers when the slide is tilted, means for operating the first 25 mentioned horizontally disposed lever, and means for operating the second mentioned horizontally disposed lever.

In testimony whereof I have signed my name to this specification in the presence of 35 two subscribing witnesses.

MATT WAGNER.
